US0D1077730S

(12) **United States Design Patent** (10) **Patent No.:** **US D1,077,730 S**
(45) **Date of Patent:** **** Jun. 3, 2025**

(54) **POWER BANK**

(71) Applicant: **SHENZHEN PANNIZHE TECHNOLOGY CO., LTD.**, Shenzhen (CN)

(72) Inventor: **Man Liao**, Shenzhen (CN)

(73) Assignee: **SHENZHEN PANNIZHE TECHNOLOGY CO., LTD.**, Shenzhen (CN)

(**) Term: **15 Years**

(21) Appl. No.: **29/913,052**

(22) Filed: **Sep. 26, 2023**

(51) LOC (15) Cl. **13-02**

(52) U.S. Cl.

USPC **D13/103**

Assistant Examiner — Charles Hwang

(57) **CLAIM**

The ornamental design for a power bank as shown and described.

DESCRIPTION

FIG. 1 is a perspective view of a power bank showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the power bank where the power bank is in a configuration of use;

FIG. 10 is an enlarged view of portion 10 shown in FIG. 2;

FIG. 11 is an enlarged view of portion 11 shown in FIG. 2;

and,

FIG. 12 is an enlarged view of portion 12 shown in FIG. 5.

The dash-dash broken lines in the drawings depict portions of the power bank that form no part of the claimed design. The dot-dash broken lines represent boundaries of the enlarged portions and form no part of the claimed design.

1 Claim, 12 Drawing Sheets
